UNITED STATES PATENT OFFICE.

CHARLES W. MCKIBBEN, OF HOUSTON, TEXAS.

TELEGRAPH-REPEATER.

1,307,558.

Specification of Letters Patent. Patented June 24, 1919.

Application filed February 27, 1918. Serial No. 219,399.

To all whom it may concern:

Be it known that I, CHARLES W. MCKIBBEN, a citizen of the United States, residing at Houston, in the county of Harris and

5 State of Texas, have invented certain new and useful Improvements in Telegraph-Repeating, of which the following is a specification.

10 My invention relates to improvements in telegraph repeaters.

The objects of my invention are to improve repeaters by simplifying the apparatus. By reducing the time factor of operation to the end that the repeater works 15 "snappy" and substantially without lag thereby increasing its capacity and clearness of transmission. By reducing the physical resistance to operation thereby maintaining a larger range or margin of current strength 20 within which the repeater will satisfactorily operate.

Other, further and more specific objects of my invention will become readily apparent to persons skilled in the art, from a 25 consideration of the following description when taken in conjunction with the drawings, wherein—

Figure 1 of the drawings shows a dia- 30 grammatic arrangement of relays and circuits showing one embodiment by which my invention may be carried into effect.

Fig. 2 shows the devices connected in multiple.

The repeater is entirely automatic and 35 does not require constant manual supervision at the repeater station.

There is no balancing resistance, to be 40 constantly adjusted to correspond with the changeable resistance of the line, due to weather variations and resultant leaks, as required by some of the repeaters of the prior art, and furthermore the means for maintaining the "opposite" or receiver relay passive or inoperative during sending operation 45 is accomplished by a means made operative by the sender and by a means that has an instantaneous time element.

The repeater, which is the subject of this 50 application, may be made up of special arrangements of circuits in connection with the ordinary telegraph relays, such as are used at any of the intermediate or way offices, consequently it is simple and easily to be understood by the inexperienced tyro 55 or "plug".

By availing myself of the use of the ordi-

nary relay, without requiring instruments to be especially constructed for the purpose, the cost of the installation is incomparably small.

60 The operation is as follows: Assume, for example, that an operator in the eastern line is sending into the western line; when he opens his key the relay R is open, the tongue r is retracted by the spring r' breaking contact with front contact r². This opens the local circuit in which the local battery LB is contained, which can be easily traced. The transmitting relay T and the short circuiting relay SR are connected in parallel 65 circuit with each other and the two coils of each of these relays are connected in parallel with each other, as shown in Fig. 2. Both sides of the circuit are thus connected in the same manner.

70 When the tongue r leaves the contact r², the tongue t of the transmitter relay T opens the west line. The tongue s of the relay SR is drawn back by the spring s' into electrical connection with its back stop contact 80 s²; this action short circuits the tongue r^a and its contact r^b of the relay R' by the wires 3 and 4, so that the local battery LB' is maintained closed so long as the circuit 85 through relay R is opened and it can only be opened when the sending operator in the east line has closed his key. When he closes his key the relay R attracts its tongue r, closing the local circuit, causing the transmitter T to close the west line circuit, 90 through the battery WB, and the relay SR to open the short circuiting circuit, containing the wires 3 and 4 and the tongue r^a that is responsive to relay R'.

95 The back contacts S² of the relays SR are adjusted very close to the front contacts so that the responsive tongues move the shortest possible distances so that the tongue of the "opposite" relay is short circuited before the circuit has been fairly opened by the sender's 100 relay R or R', as the case may be.

105 There is no spark between the tongue s and the back contact s², because, while these instrumentalities are opening and closing a circuit around the tongue and contact of the "opposite" relay, the local circuit which they control is already closed by them. Therefore, the adjustment may be very close to reduce the time period of operation and furthermore the spring s' may be made relatively strong so as to be quickly and ac- 110 tively operative.

The resistance rheostat RH bridges the break made between the tongue *r* and the contact *r*². The resistance is relatively high and substantially non-inductive and takes 5 the "kick" of discharge of the magnets of T and SR. These magnets, however, being connected in multiple, see Fig. 2, discharge into each other, and the two coils of these relays being connected into circuit in multiple 10 with each other, further reduce the effect of their self inductance at the said break so as to practically kill the spark.

The resistance RH is very high, serving to just maintain a very slight current in the 15 circuit when said contacts are open.

It may be replaced by a suitable condenser or dispensed with altogether without materially affecting the operation of the repeater.

It will be manifest to persons skilled in 20 the art when a sender on the west line desires to send into the east line that the instruments appertaining to that line will work in the same manner, as the arrangements for one line is duplicated for the other.

25 My repeater is fast in action, because of the quick, lively discharge of the coils; because the moving part, the tongue of the ordinary relay, has relatively little momentum and inertia. It is simple and easily to 30 be understood, because there are no unusual special instruments in its composition.

If desired, an ordinary sounder may be connected in local circuit with the transmitters T and T' so that the repeater operator 35 may hear and receive from the respective sounders when either side is sending.

Having described my invention, what I claim is:—

1. A telegraph repeater comprising two 40 line relays, one for each side and each relay connected to the ground through a line battery; a transmitter relay, for each side, controlled through a local battery by the respective line relay; a short circuiting relay 45 for short circuiting the contacts of the relay of the opposite side, the coils of the transmitter relay and of the short circuiting relay of each set being in parallel circuit with each other.
- 50 2. A telegraph repeater comprising two line relays, each connected directly to

ground, through a line battery; one on each side; a transmitter relay on each side controlled through a local battery by the respective relay and a relay for each side having a back contact to short circuit the contacts of the relay of the opposite side when the local circuit containing said short circuiting relay is open. 55

3. A telegraph repeater comprising two 60 line relays, each connected to the ground through a line battery; a transmitter for each side, controlled through a local battery, by the respective line relay and a relay for each side in parallel circuit with its 65 transmitter, responsive to the respective line relay to short circuit the contacts of the passive or opposite line relay when the circuit through the active line relay is open.

4. A telegraph repeater comprising an ordinary line relay having its coils connected in parallel with each other and each said line relay connected to the ground through a line battery and to the respective line; a transmitter relay of the same character as the line 75 relays on each side, in a local battery circuit, responsive to the respective line relays and another relay of the same character, in parallel with the transmitter relay adapted to short circuit the contacts of the opposite line 80 relay when its line circuit is open.

5. A telegraph repeater having two duplicate sides, each side having a Morse relay connected to the ground through a battery and to the opposite main line; a Morse relay 85 transmitter and another similar short-circuit relay, connected in parallel circuit with the transmitter relay, and adapted to short circuit the contacts of the opposite line relay on its back contact, said transmitter relay 90 and said short circuiting relay in a local circuit controlled by said line relay, all of said relays having their respective coils connected in parallel circuit with each other.

In testimony whereof I hereunto set my 95 hand in the presence of two subscribing witnesses.

CHARLES W. MCKIBBEN.
